UNITED STATES PATENT OFFICE.

JOHN GROUSS, OF ELIZABETH, NEW JERSEY, ASSIGNEE OF ONE-HALF TO CLARENCE E. PRYOR, OF ELIZABETH, NEW JERSEY.

LIGHT-CUT-OUT SWITCH FOR FIRE-HOUSES.

1,218,855.

Specification of Letters Patent. Patented Mar. 13, 1917.

Application filed March 24, 1916. Serial No. 36,326.

To all whom it may concern:

Be it known that I, JOHN GROUSS, a citizen of the United States, and a resident of Elizabeth, in the county of Union and State 5 of New Jersey, have invented a new and Improved Light-Cut-Out Switch for Fire-Houses, of which the following is a full, clear, and exact description.

This invention relates to apparatus for 10 automatically cutting out the lights in a fire house upon the lapse of a predetermined period of time, say four minutes more or less, after a fire alarm has been turned in, which causes the automatic turning on of 15 the lights in the fire house, it being understood that it is the usual custom in certain fire companies for all the members to leave the house with the fire fighting apparatus when an alarm comes in, and unless automatic 20 means be provided for cutting out the lights they will remain until the members of the company return from the fire. While apparatus has been proposed for automatically cutting out the lights, the arrangement 25 of the various instrumentalities is such that with each succeeding alarm the lights will be again turned on.

It is the general object of the present invention to improve automatic cut-out apparatus whereby the lights will remain cut 30 out after the first alarm and until the apparatus is reset, when the members of the fire company return to the fire house.

A more specific object of the invention is 35 the provision of a clockworks that is normally held stopped by a constantly energized electromagnet which is in the fire alarm circuit of a town or municipality, so that when the circuit is broken by the sending in of a fire alarm the magnet becomes deenergized and the clockworks is set off so that it will run for a predetermined period of time, when it releases a trip which causes the lights to be extinguished, the 40 lights being automatically turned on by the deenergizing of the electromagnet at the same time the clock begins to run.

With such objects in view, and others 45 which will appear as the description proceeds, the invention comprises various novel

features of construction and arrangement of 55 parts which will be set forth with particularity in the following description and claims appended hereto.

In the accompanying drawings, which illustrate certain embodiments of the invention and wherein similar characters of reference indicate corresponding parts in all the views,

Figure 1 is a front view of the automatic cut-out switch in its normal or set condition;

Fig. 2 is a similar view showing the lighting switch closed and the parts in a position just prior to the automatic opening of the lighting switch and the stopping of the 70 clockworks;

Fig. 3 is a detail view of the devices for controlling the starting and stopping of the clockworks;

Fig. 4 is a detail sectional view on the 75 line 4—4, Fig. 2;

Fig. 5 is a diagrammatic view of the circuit connections; and

Fig. 6 is a view of a modified form of the invention especially adapted for gas light- 80 ing systems.

Referring to the drawings, A designates a box, cabinet or case in which are arranged the lighting cut-out switch B, C the clockworks, and D the electromagnetic device for holding the switch normally open. This box is arranged in the fire house at any suitable point and is provided with a glazed door 1 which is adapted to be opened for the purpose of setting the apparatus. 90

The switch B, as well as the other parts of the apparatus, are mounted on a plate or slab 2 of slate or other insulating material. In the present instance the switch is shown as consisting of two blocks of insulating 95 material 3, and in each block, as shown in Fig. 4, is a vertical chamber 4 that contains mercury 5, and into this mercury dips a finger-like contact 6. The contacts 6 are electrically connected together at their upper ends by a bar 7 which is fastened to a strip of insulation 8. Fastened to each block 3 is a metallic terminal connector 9 formed with a stud 10 which extends into

the block 3 and is partially surrounded by mercury. The lighting circuit wires 11 and 12 are connected with the terminal connectors 9, and connected with these wires 5 are lamps 13 suitably arranged in the fire house. Normally the contacts 6 are held out of the mercury, as shown in Fig. 5, so that the lighting circuit is open, but when the switch B closes, by the contact 6 drop- 10 ping into the mercury, the lamps 13 will be lighted. The blocks 3 are separated from each other so as to reduce any likelihood of a short circuit.

To normally hold the switch B open, the 15 electromagnetic device D is employed. This comprises an electromagnet 14, fastened by a bracket 15 to the plate 2, and the armature 16 of the electromagnet is carried by a lever 17 that is fulcrumed at 18. The end 19 of 20 the lever has an opening 20 through which passes the threaded stem 21 rigidly secured to the cross-bar 8 of the switch, and on the stem is a nut 22 that engages the top side of 25 the lever and enables an adjustable connection to be made between the lever and the movable element of the switch. The windings of the electromagnet 14 are connected with the wires 23 and 24 of the fire alarm circuit, there being a lightning arrester 25 connected across the alarm circuit. The 30 alarm circuit is normally closed so that current constantly flows through the electromagnet, and consequently the lever 17 is held in such a position that the cut-out switch B 35 will be open-circuited. When the electromagnet 14 is deenergized the movable element of the lever will gravitate to closed-circuit position and close the lighting circuit in the fire house, which circuit will be kept 40 closed until the lapse of a predetermined period of time.

The clockworks C determines how long the lighting circuit will be kept closed. This mechanism C comprises a suitable arrangement of intermeshing gears driven by a 45 spring 26. The gear wheel 27 of the train of gears has a pin 28 with which is engageable stopping and starting dogs 29 and 30. The dog 29 is carried by the lever 17, and when 50 the lever is released by the electromagnet the dog 29 moves downwardly out of the path of the pin or projection 28, so that the clock will be permitted to run under the motive force of its spring 26. The stopping dog 30 is normally raised out of the path of the pin 28, being so held by a spring 31 coiled around the shaft 32 to which the dog 30 is connected. The dog 30 is thrown into the path of the pin 28 by means of an arm 33 connected with 55 the shaft 32 and arranged to be engaged by a pin 34 on the wheel 35 of the train of gears. This pin makes one revolution during the actuation of the clockworks and determines the period of lighting of the lamps in the fire

house. Normally the pin 34 is to the right of 65 the arm 33, as shown in Fig. 1, and when the wheel 35 makes a complete revolution the pin 34 will engage the arm 33 on the left side and move the arm so as to throw the stop dog 30 downwardly to engage the pin 28 on the 70 wheel 27 and thereby stop the clockworks. The pin 34 also controls the device for opening the switch B. This device comprises a vertical rod 36 slidably mounted in brackets 75 37 and 37' and having its upper end 38 engageable with the cross bar 8 of the switch. Between the bracket 37' and a collar 39 on the rod 36 is a helical compression spring 40 which tends to throw the rod 36 upwardly. On the rod 36, which has its lower end extending downwardly out of the box A, is a shoulder 41 with which is engageable the extremity 42 of a catch 43, the same being fulcrumed at 44 on the bracket 37' and having a finger 45 located in the path of the pin 34, 80 so that after the wheel 35 has almost completed the revolution the pin 34 will strike the finger 45 and disengage the extremity 42 of the catch from the shoulder 41, whereby the rod 36 will be thrown upwardly by the 85 tension of the spring 40 and cause the switch B to open. After the switch has been thus automatically opened it remains so until the apparatus is again manually reset. To do this the box is opened and the arm 33 sprung 90 forwardly and passed over the pin 34, so as to be at the left side thereof, as shown in Fig. 1. The lever 17 is returned to normal position, where it will be held by the electromagnet 14, it being understood that the magnetic pull of this magnet is not sufficient to 95 restore the lever 17 after the lever has been tripped. The rod 36 is pushed downwardly against the tension of its spring 40 and is held in its lowered position by the resetting 100 105 of the catch 43. The apparatus is now ready to be actuated by the sending in of an alarm of another fire.

In the modification shown in Fig. 6 the apparatus is designed for controlling gas 110 lights, and consequently the electric cut-out switch B shown in Figs. 1, 2 and 5 is dispensed with. In the basement, or in any other suitable point in the fire house is arranged a cut-out valve E in the gas supply 115 pipe 46, there being a by-pass 47 around the valve E, so that there will always be a low flame burning in the lamps. The valve is opened and closed by a lever or equivalent means 48 which carries a weight 49 that operates to lower the lever and thus open the valve when an alarm is sent in. The spring actuated catch 50 normally holds the lever 48 raised. This catch is connected by a bell-crank lever or equivalent means 51 with a 120 rod or equivalent means 52 that carries an actuating weight 53, the rod 52 extending upwardly into the box A. Connected with the 125

upper end of the element 52 is an adjustable collar 54 which is engaged by a pivoted catch 55 disposed in the box A, and so arranged that the lever 17', corresponding to the lever 17, Fig. 1, will hold the catch 55 in the position shown in Fig. 6 as long as the magnet 14' is energized. When the magnet is deenergized the lever 17' drops and releases the catch 55, so that under the action 10 of the weight 53 the element 52 moves downwardly and disengages the catch 50 from the lever 48, so that the weight 49 will open the valve E and light the lamps to full power.

To close the valve E, the lever 48 is raised 15 by a weight 56 which is heavier than the weight 49. This weight is connected by a suitably guided cord 57 with the lever 48, and it is normally held raised by a spring-actuated catch 58 that is connected by a 20 cord 59 with the lever 43', corresponding to the lever 43, Fig. 1, so that when the pin 34' actuates the bell-crank lever 43', the cord 59 is pulled so as to release the catch 58 and allow the weight 56 to drop and 25 raise the lever 48 to normal position. The weight 56 is restored to normal position, when the catch 58 will automatically set by pulling upwardly on a resetting device 60 that is mounted on the box A or any suitable place, and which is connected by a cord 30 61 with the weight 56. In resetting the device the element 52 is raised and the catch 55 held engaged with the shoulder 54 by returning the lever 17' to normal position.

35 To prevent splashing out of the mercury from the cups 4, the lower ends of the contacts 6 are pointed, whereby the reliability of the switch is insured.

From the foregoing description taken in 40 connection with the accompanying drawings, the advantages of the construction and method of operation will be readily understood by those skilled in the art to which the invention appertains, and while I have 45 described the principle of operation, together with the apparatus which I now consider to be the best embodiment thereof, I desire to have it understood that the apparatus shown is merely illustrative and that 50 such changes may be made when desired as fall within the scope of the appended claims.

Having thus described my invention, I claim as new and desire to secure by Letters Patent:

55 1. The combination of a normally closed fire alarm circuit and an electromagnet therein and normally energized, with a fire house lighting system, a device for throwing the system into and out of operation and 60 controlled by the electromagnet to throw the said device into operation, and a clock-works determining the period during which the lighting system will remain in use, and including means whereby the lighting sys-

tem will be thrown out of use and remain 65 so until the apparatus is manually reset after the receiving of an alarm.

2. The combination of a normally closed alarm circuit and a normally energized electromagnet therein, with a fire house lighting 70 system, a device for throwing the said system into service, means adapted to be manually reset and normally held by the energized electromagnet for holding the device in service cut-out position and adapted, 75 when the magnet is deenergized, to permit the device to move to service position, a clock-works for determining the period in which the lighting system will be in service, means controlled by the electromagnet for control- 80 ling the starting of the clockworks, means having a movement sufficient for throwing the device to service cut-out position and insufficient to reset the first mentioned means to normal position, a device actuated by the 85 clockworks for controlling the last-mentioned means, and means for automatically stopping the clockworks after the lapse of a predetermined period of time.

3. The combination with an alarm circuit 90 normally closed and a magnet in the said circuit, with a fire house lighting system, a device for throwing the system into and out of service, a member normally held by the electromagnet to retain the device in serv- 95 ice cut-out position and released by the electromagnet when the same is deenergized, to permit the device to throw the system into service, a clockworks, a dog connected with the member to control the starting of the 100 clockworks when the magnet is deenergized, a dog automatically actuated by the clock-works for stopping the same after the lapse of a predetermined period of time, a mem- 105 ber actuated by the clockworks just prior to the stopping thereof, and means controlled by the last-mentioned member for causing the said device to be thrown to serv- ice cut-out position.

4. The combination of a normally closed 110 fire alarm circuit and a normally energized magnet therein, with a fire house electric lighting system, a normally open switch in the said system, a member normally held by the energized electromagnet to hold the 115 movable element of the switch in open cir- 120 cuit position, a clockworks, a device con- trolled by the clockworks for moving the movable element of the switch to open cir- cuit position, a dog controlled by the electro- 125 magnet to permit the clockworks to start when the electromagnet is deenergized, and a device for automatically stopping the clockworks after the same has caused the switch to automatically open.

5. The combination of a fire alarm cir- 125 cuit and an electromagnet normally ener- gized, with a fire house lighting system in-

cluding a device for throwing the lights into and out of use, said device including a movable element mounted to automatically move to service position, manually reset means controlled by the electromagnet for holding the element out of service position, means tending to move the element from service to non-service position, and a mechanism active after a predetermined lapse 10 of time after the throwing into service of

the lighting system for causing the last-mentioned means to throw the element to non-service position.

In testimony whereof I have signed my name to this specification in the presence 15 of two subscribing witnesses.

JOHN GROUSS.
